his Atty.

United States Patent Office.

AMASA C. KASSON, OF MILWAUKEE, WISCONSIN.

Design No. 4,407, dated October 11, 1870.

DESIGN FOR A HINGE.

The Schedule referred to in these Letters Patent and making part of the same.

To all whom it may concern:

Be it known that I, AMASA C. KASSON, of Milwaukee, in the county of Milwaukee and State of Wisconsin, have invented a new Design for a Hinge, of which the following is a specification, reference being had to the accompanying drawing.

The invention in this case is fully shown by the accompanying photographs,

Figure 1 being a front view of the two parts of the hinge detached, and

Figure 2 being a rear edge view of the hinge closed.

As shown, each leaf is made with a conical enlargement, about midway of its length, on the back edge, in one of which is formed the socket, the other having a corresponding pintle, and each leaf having a

bead, extending from the apex of the cone to the end of the leaf, where it terminates in an ornamental knob or acorn.

The adjoining or back edges of each leaf are formed with an incline corresponding with the cone, so that, when united, the two parts fit together throughout their length.

Having thus described my invention,

What I claim is—

The design for a hinge, substantially as shown and described.

AMASA C. KASSON.
